HORACE D. BLACK, OF UXBRIDGE, ENGLAND, ASSIGNOR TO BELL PUNCH COMPANY,
LTD., OF LONDON, ENGLAND

INKING DEVICE

Application filed May 2, 1929. Serial No. 359,889.

This invention relates to an inking device and particularly to a small and compact inking device adapted for use in a ticket printing and issuing machine.

5 The object of the invention is to improve the type of inking device disclosed in the application of Christopher Frederick Webb, Serial No. 260,268, filed March 9, 1928, which shows a ticket printing and issuing machine 10 arranged to selectively print different types of tickets from a single strip, the inking device being arranged to ink only the plate which is adapted to print the desired ticket. Primarily this invention has for its purpose 15 the provision of an inking device for a machine of this type which is readily removable for cleaning or adjustment and which is automatically released from and connected with the operating mechanism of the ticket 20 issuing machine.

A further object relates to the provision of an adjustable means for regulating to a fine degree the amount of ink delivered by the inking roller to the printing plate.

25 In the accompanying drawings:

Fig. 1 is a vertical sectional view of various parts of a mechanism of the type disclosed in the said application which are directly operative to produce actuation of the inking 30 device.

Fig. 2 is a sectional view on line 2—2 of Fig. 1.

Fig. 3 is a vertical section through the inking assembly.

35 Fig. 4 is a front elevation of the inking assembly with the cover raised.

Fig. 5 is a horizontal section through the inking assembly showing the position of the well.

40 Fig. 6 is a perspective view of the adjustable blade which serves to regulate the ink carried by the transfer roller to the inking roller.

The main shaft of the machine indicated at 45 2 is arranged to be driven through a predetermined number of cycles upon depression of a suitable key of the ticket issuing mechanism through a clutch means of the type disclosed in the application referred to. This 50 shaft carries a platen 4 on the periphery of

which are removably secured various printing plates of which one, designated at 6, is illustrated. Selective printing by any one of these plates is accomplished by depression of the proper key. A series of cams, of which 55 one 8 is illustrated, serve to actuate the ticket feeding means and also the inking device so as to produce inking of the selected type plate and produce the printing and issuance 60 of the desired type of ticket.

In accordance with the present invention, a bracket 10 is secured to the wall of the housing at the rear of the machine. Sloping downwardly and forwardly from the bracket 10 are a plurality of parallel rods 12 which 65 extend to the front of the casing in a position easily accessible to an operator. The bracket and rods serve as a support for the inking assembly.

The inking assembly consists of a casing 70 preferably formed of sheet metal and which consists of a bottom 14 integral with sides 16 and 18 and provided with front and rear flanges 20 and 22 respectively. To the rear flange is bolted or riveted an upwardly extending plate 24 which forms the rear wall of the casing. Similarly, to the front flange 20 there is secured a plate 26 of less height than plate 24 which forms the forward wall 75 of the casing. Each of plates 24 and 26 80 extends downwardly below bottom plate 14 as will be clear hereafter. A top plate 28 of suitable shape as shown is provided with lugs 32 by means of which it is pivoted between side plates 16 and 18. The portion of 85 cover 28 extending rearwardly beyond lugs 32 is bent upwardly to a slight degree as shown. Rear plate 24 is secured so as to spring 90 slightly in a forward direction and contact with the upturned end 34 of the cover plate. By exerting a force on this up-turned end above lugs 32, it will be observed that cover 28 will be releasably held in closed position but may be raised against the pressure of 95 plate 24 when up-turned end 34 passes below the level of lugs 32 and plate 24 will tend to hold the cover open. It can be moved beyond this position to the fully opened position indicated in dotted lines in Fig. 3.

Pairs of aligned holes 35 are provided in 100

the portions of plates 24 and 26 extending downwardly below plate 14. These holes are arranged so as to receive the supporting rods 12 so that the inking assembly may be slid upwardly into operative position, or downwardly to a position accessible to the operator. Extending through the lower portion of plate 26 is a stud 36 which is embraced by an elongated slot 38 in a latching plate 40. At its outer end, plate 40 is provided with a turned portion 42 which may be engaged by an operator's finger to impart longitudinal sliding movement to plate 40. A lug 44 at the inner end of plate 40 extends rearwardly into a slot aligned with slot 38 so as to restrain the plate from pivotal motion about stud 36 and confine it to a rectilinear sliding motion. A spring 46 secured between lug 44 and the inner end of stud 36 serves to normally move the plate to the outward position shown in Fig. 4. Plate 40 is provided with an aperture 48 which, when the plate is pressed inwardly against the tension of spring 46, is adapted to align with aperture 35 formed in the left hand side of plate 26. When the plate is moved under the tension of spring 46, however, aperture 48 is out of alignment with aperture 35, as illustrated in Fig. 4. A notch 50 provided on the inner side of the left hand rod 12 is arranged to be engaged by the periphery of aperture 48 when the inking assembly is in position to cooperate with the platen. It will be obvious that pressure upon end 42 of plate 40 will serve to disengage the periphery of aperture 48 from the notch and thereby permit the assembly to be brought to accessible position. On the other hand, in replacement of the assembly as the assembly slides forwardly along the rods apertures 35 and 48 will be in alignment. As soon, however, as the assembly reaches operative position, the latching plate will snap into notch 50, thereby serving to releasably latch the assembly automatically in proper position.

A shaft 52 journaled in walls 16 and 18, carries fixedly a transfer roller 54. To the left hand end of this shaft is secured a crank 56 by means of which the shaft is driven in a manner later described. Roller 54 is arranged to carry ink from the well 55 of the shape illustrated in the drawings to an inking roller. The amount of ink thus delivered by a clockwise motion of roller 54 as viewed in Fig. 3 may be finely adjusted by means of a plate 58 which, as shown in Fig. 6, is provided with lugs 60 at its forward edge receivable within slots 62 in the side walls 16 and 18. A thumb screw 64 passes through a hole 66 in plate 58 and is threaded into a transverse rod 68. By adjustment of this screw, the plate may be pivoted about lugs 60 and the engagement of its blade 70 adjusted with respect to roller 54. By this means a very

thin film of ink may be carried by roller 54 to inking roller 72.

Inking roller 72 is rotatably mounted upon a pin 74 which has flattened ends 76 slidably mounted in upwardly extending slots 78 in the upper portions of walls 16 and 18.

Extending outwardly beyond flattened portions 76 are circular members 80 which are arranged to be received within hooks 82 formed at the rear ends of arms 84. Arms 84 are rigidly joined together and to an upwardly extending arm 86, the arms being journaled upon a transverse bearing rod 88 so as to form, in effect, a bell crank lever as shown in Fig. 1. A spring 90 normally serves to rotate this bell crank in a counter-clockwise direction, as viewed in Fig. 1, against a stop 92 carried by the housing of the machine. At the outer end of arm 86 there is provided a transverse pin 96 which carries a sliding cam following roller 94 adapted to be engaged by cams 8. This roller is of the type disclosed in the application referred to above and is positioned along pin 96 in accordance with the key which is depressed so as to be brought into line with the path of movement of one of the selected cams 8. By this arrangement, during an operation of the machine, only that plate which is to be used is inked by roller 72, which is raised into engagement therewith by rocking of the bell crank lever by the proper cam 8.

Driving motion is imparted to transfer roller 54 through the medium of a shaft 98 provided with a radially extending pin 100 which is arranged to engage crank 56. The type of engagement disclosed is operative even though shaft 98 is slightly out of alignment with shaft 52 as indicated in Fig. 1. Shaft 98 is provided with a suitable sprocket wheel and is driven from the main shaft through a chain which also drives the shaft carrying the feed roller. Thus, during every rotation of shaft 2, rotary movement is imparted to feed roller 54, resulting in inking thereof and transfer of a regulated quantity of ink to inking roller 72.

By reason of the driving connections for shaft 52 and the hook arrangements on the ends of arms 84 engaging pins 80, the inking device is automatically brought into driven condition upon movement to its operative position. Likewise movement from the operative position automatically serves to disengage both the driving connections of shaft 52 and the lifting connections for the inking roller.

The well 55 is preferably for the form shown and is readily removable for cleaning or replacement of ink.

What I claim and desire to protect by Letters Patent is:—

1. An inking device for a printing mechanism comprising an inking assembly, a fixed sloping supporting track on which the inking

assembly is slidable with a horizontal component of motion either to a position in which it is in operative relationship to the printing mechanism or to a position where it is accessible to an operator, and a latch carried by the inking assembly and arranged to engage the track when the assembly is in the former position.

2. An inking device for a printing mechanism comprising an inking assembly, a fixed sloping supporting track on which the inking assembly is slidable with a horizontal component of motion either to a position in which it is in operative relationship to the printing mechanism or to a position where it is accessible to an operator, and a latch carried by the inking assembly and arranged to engage the track when the assembly is in the former position, said latch comprising a spring operated member manually movable to a released position against the action of the spring.

3. An inking device for a printing mechanism comprising supporting means, an inking assembly including an inking roller, said inking assembly being movable from a position on the supporting means in which it is in operative relationship to the printing mechanism to a position where it is accessible to an operator, and means for moving the inking roller relatively to a printing cylinder arranged for automatic engagement with and disengagement from the inking roller when the inking assembly is moved respectively towards and from its operative position, said means including a rotating element carried by the assembly engageable with a rotating driving element, the elements being rotatable about axes transverse to the direction of movement of the assembly.

4. An inking device for a printing mechanism comprising supporting means, an inking assembly including an inking roller, said inking assembly being movable from a position on the supporting means in which it is in operative relationship to the printing mechanism to a position where it is accessible to an operator, and means for moving the inking roller relatively to a printing cylinder arranged for automatic engagement with and disengagement from the inking roller when the inking assembly is moved respectively towards and from its operative position, said means including a crank and pin one of which is carried by the assembly and the other of which is mounted independently of the assembly.

5. An inking device for a printing mechanism comprising supporting means, an inking assembly including a well, an inking roller, and a transfer roller for transferring ink from the well to the inking roller, said inking assembly being movable from a position on the supporting means in which it is in operative relationship to the printing

mechanism to a position where it is accessible to an operator and driving means for rotating the transfer roller, said transfer roller entering automatically into position to be rotated by the driving means and automatically leaving said position when the inking assembly is moved respectively towards and from its operative positions, the driving means comprising a crank and pin one of which is carried by the transfer roller and the other of which is mounted independently of the assembly.

6. An inking device for a printing mechanism comprising supporting means, an inking assembly including a well, an inking roller, and a transfer roller for transferring ink from the well to the inking roller, said inking assembly being movable from a position on the supporting means in which it is in operative relationship to the printing mechanism to a position where it is accessible to an operator and driving means for rotating the transfer roller, said transfer roller entering automatically into position to be rotated by the driving means and automatically leaving said position when the inking assembly is moved respectively towards and from its operative positions, the driving means comprising a crank and pin one of which is carried by the transfer roller and the other of which is mounted independently of the assembly, and means for latching the inking assembly in operative position.

7. An inking device comprising a casing, an inking roller mounted in the casing, a transfer roller mounted in the casing, a removable well within the casing, said transfer roller being arranged to carry ink from the well to the inking roller, an adjustable blade arranged to control the ink carried by the transfer roller to the inking roller, a supporting track on which the casing is slidable, and a latch carried by the casing and arranged to engage the track when the casing is in a determined position.

8. An inking device comprising a casing, an inking roller mounted in the casing, a transfer roller mounted in the casing, and a well within the casing, said transfer roller being arranged to carry ink from the well to the inking roller, an adjustable blade arranged to control the ink carried by the transfer roller to the inking roller, said blade being pivoted in the casing, and a screw threaded into a fixed part of the casing and engaging said blade to adjust its position relative to the transfer roller said blade contacting with the transfer roller above the surface of ink in the well.

In testimony of which invention, I have hereunto set my hand, at London, England, on this 26th day of March, 1929.

HORACE D. BLACK.
